UNITED STATES PATENT OFFICE.

THOMAS R. GRIFFITH, OF DOVER, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed December 12, 1923. Serial No. 680,169.

To all whom it may concern:

- Be it known that I, THOMAS R. GRIFFITH, a citizen of the United States of America, residing at Dover, in the county of Morris, 5 State of New Jersey, have invented certain new and useful Improvements in Electron-Discharge Devices, of which the following is a full, clear, concise, and exact description.
- 10 This invention relates to electron discharge devices and more particularly to high power vacuum tubes, its object being to improve the electrode supporting structure in this device.
- 15 In high power vacuum tubes of certain types, the cathode and grid electrodes are arranged between two blocks of insulating material. The insulating blocks are generally spaced apart by means of metallic 20 rods, which are usually attached to the insulating blocks by nuts on both sides of the blocks or by swedging or enlarging the ends of the metallic rods. These methods produce strains in the insulating block which 25 are liable to cause fracture of the block.
- According to this invention, each block 30 of insulating material is provided with an aperture for the respective metallic rod, and in addition, one side of each insulating block is provided with an elongated slot or 35 groove, adjacent the aperture. The metallic rod is inserted in the apertures in the insulating blocks and the rod has a folded portion at right angles to the axis of the rod which is seated in the elongated slot in the insulating blocks. The space is then 40 filled with cement, to securely hold the rod in the insulating blocks. This arrangement prevents the rod becoming loose in the insulating blocks. It eliminates entirely the 45 undesirable breakage of the insulating block due to the strain occasioned by the pressure required to provide a tight connection between the metal rod and the insulating blocks. The cement allows the rod to take its natural shape in the aperture, without tension, and when set, provides an integral mass surrounding the rod.

50 Referring to the drawings: Fig. 1 illustrates an electron discharge device embodying this invention.

Fig. 2 is a plan view of the apertured insulating block.

55 Fig. 3 is a view in cross section of the joint.

Referring to Fig. 1, an electron discharge device is illustrated comprising a cylindrical metal anode 10, with a metallic cap 11, hermetically closing one end. A glass portion 12, with a reentrant neck 14 is joined 60 to the metal anode 10 at 13. The joint 13, between the metal anode 10 and glass portion 12, may be made in accordance with W. G. Houskeeper, U. S. Patent 1,294,466. A metallic collar 15 encircles the neck 14, 65 and is frictionally held thereon. The metallic collar 15 is provided with integral lugs 16, through which the rods 17 are supported in the usual manner. The rods 17 are bent inwardly to register with the apertures 26 in the insulating block 19. The insulating block 19 is provided with apertures 20, through which the filament leads 21 extend. The grid lead 23 extends through aperture 22 in the insulating block 70 19 and is enclosed in the tubular member 24 which is hermetically sealed at 25. The sealing arrangement is not essential to an understanding of this invention, since this feature is described in W. G. Houskeeper 75 U. S. Patent 1,293,441.

The insulating block 19 is provided with elongated slots or grooves 27, adjacent one side of the block and projecting toward the centre of the block from the cooperating 80 apertures 26.

The metallic rod 17 is inserted in the aperture 26 adjacent the groove 27 and is bent to form an integral projection 18, at 85 right angles to the vertical portion of the rod. The projection 18 is seated in the slot or groove 27.

The slot 27 is thereafter filled with an aluminum oxide cement 28, which is commercially known as "alundum."

90 This aluminum oxide cement consists of electrically fused alumina with a ceramic bond and can be obtained in granular or powder form. The dry cement is mixed with the proper amount of water to form a mass of the required consistency for working. This cement flows very freely and fills the crevices around the rod 17 in the slot 27 and aperture 26.

95 The assembly is then placed in an oven and heated to a temperature of approximately 1,000° C. At this temperature the cement vitrifies and forms a solid mass with the insulating blocks. This construction 100 provides a highly efficient connection be- 110

between the metallic member and the insulating members and at high temperatures it is not subject to fracture. Although this invention has been described with reference to the aluminum oxide cement, it is entirely within the scope of the invention that other cements having the required qualities of tenacity and resistance to fracture can be used with equal results. The invention is only to be limited within the scope of the appended claims.

What is claimed is:

1. In an electron discharge device, an apertured member, a groove adjacent said aperture, a supporting rod having a projection positioned in said groove, and a cement enclosing said projection of said supporting rod in said groove.
2. An electron discharge device comprising an apertured insulating block, a radial groove on one side of said block, a rod inserted in said block, a portion of said rod being of irregular formation and seated in said groove, and a fused alumina cement surrounding said rod and filling said groove in said insulating block.
3. An electron discharge device comprising an apertured block, a depression on one

side of said block, a supporting rod passing through said block, said rod having a horizontal folded portion seated in said depression, and an electrically fused alumina binder enclosing the folded portion of the rod in said block.

30

4. An electron discharge device comprising an apertured insulating block, said block having radial grooves on one side thereof, supporting rods in said block having integrally folded portions, said folded portions being positioned in said grooves, and an aluminum oxide binder in said grooves.

35

5. In an electron discharge device, an apertured insulating block, a groove in said block connecting with said aperture, a metallic rod inserted in said apertured insulating block, said rod having a folded portion seated in said groove, and a binder enclosing said folded portion in said groove, said binder being capable of withstanding temperatures of the order of 1000° C.

40

In witness whereof, I hereunto subscribe my name this 5th day of December A. D.,

50

1923.

THOMAS R. GRIFFITH.
